APPARATUS FOR FORMING ONE-PIECE
PLYWOOD CORNER UNITS

Harold McGowan, Central Islip, N. Y., assignor
of one-half to Bert Raskin, Brightwaters,
N. Y.

Original application May 17, 1941, Serial No.
394,022. Divided and this application November
13, 1941, Serial No. 418,970

4 Claims. (Cl. 144—259)

The present invention relates to an apparatus for forming one-piece plywood corner units.

This application is a division of my copending application filed May 17, 1941, and bearing Serial Number 394,022.

One of the important objects of the present invention is to provide an apparatus for facilitating the bending of a pre-channelled piece of plywood material so that an integral corner unit may be subsequently formed.

A further object of the invention resides in the provision of an apparatus of the above mentioned character wherein steam is utilized for saturating the pre-channelled piece of plywood to soften the same, thereby facilitating the easy bending of the plywood to form the angular corner unit.

A still further object is to provide an apparatus that includes a table upon which means is provided for clamping a portion of the plywood material, swingable steam pipes being arranged at the front of the table for delivering steam to the pre-channelled extending portion of the plywood material.

Another object of the invention is to provide an apparatus of the above mentioned character that will at all times be positive and efficient in its operation as well as being strong and durable.

Other objects and advantages will become apparent from the accompanying drawing and description.

In the drawing, forming a part of this specification and in which like references designate corresponding parts throughout the several views:

Figure 1 is a perspective view of the apparatus employed for treating and bending a sheet of the pre-channelled plywood material from which the corner unit is to be formed.

Figure 2 is a fragmentary front elevation of the table, showing the perforated steam pipes in section.

Figure 3 is a vertical sectional view taken approximately on the line 3—3 of Figure 2.

Figure 4 is a fragmentary transverse section through the table, showing a sheet of pre-channelled plywood material clamped thereon and ready for the steam treatment; and

Figure 5 is a view similar to Figure 4 showing the plywood sheet after having been subjected to the steam treatment and the outwardly projecting portion of the plywood sheet being bent downwardly, with the lower steam pipe swung away from the table.

In the drawing, the numeral 1 designates the

work bench or table over the front edge of which extends a metallic angular straight edge 2. A vertically movable clamping jaw 3 is arranged above the forward edge portion of the table.

Springs 4 normally hold the clamping jaw 3 in a raised position. Suitable screw-threaded rods 5 are mounted at their lower ends in suitable brackets 6 secured at the respective ends of the table and these rods extend upwardly and freely through guides 7, carried by the respective ends of the jaw 3. Handled sleeves 8 are threaded on the upper ends of the screws 5 and coact with the guides 7 for moving the jaw 3 downwardly into clamping engagement with the plywood sheet. The springs normally hold the clamping jaw raised sufficiently to permit the plywood sheet to be readily and easily positioned on the table.

A transversely movable gauge bar 9 is adjustably mounted on the upper face of the table 1 and the manner in which this bar engages the inner edge of the plywood sheet is clearly illustrated in Figures 4 and 5 of the drawing.

The table 1 is formed with suitable slots 10 to accommodate the fastening elements 11, whereby the gauge bar 9 may be moved and secured in any transversely adjusted position on the table 1.

Upper and lower steam pipes 12 and 13 extend longitudinally across the front of the table. The opposed sides of these steam pipes are formed with steam outlet openings 14 throughout the length of the steam pipes. These steam pipes may be supported in any suitable manner.

A steam supply pipe 15 delivers live steam from a suitable steam boiler 16 to the inner ends of the steam pipes 12 and 13 while the outer ends of the perforated steam pipes have drain pipes 17 associated therewith.

Adjacent their connection with the steam supply pipe 15, the steam pipes 12 and 13 have swivel joints 12' and 13' associated therewith to permit either steam pipe to be swung outwardly and away from the table when bending the steam heated plywood sheet.

A control valve 18 is associated with the steam supply pipe 15, and similar valves 19 and 20 are associated with the perforated steam pipes 12 and 13, as clearly shown in Figure 1 of the drawing.

With reference now to Figure 4, there is shown a sheet of plywood material 21 from which the corner unit is to be formed. In the instant case, a saw cut is made in the longitudinal center of the plywood sheet and this saw cut 22 extends from the top face to the approximate center of the thickness of the plywood sheet.

According to the quality of the center ply, the depth of the saw cut is adjusted so that the fibers of the center ply will break, forming a bridging when the pre-channelled plywood sheet is steam treated and bent. This bridging will make a good bond with the glue and extender or cement used to reinforce the corner unit.

In forming my improved plywood corner unit, the pre-channelled plywood sheet is placed on the table 1 and the gauge bar 9 is adjusted to position the groove 22 directly adjacent the outer face of the metal straight edge 2 on the forward edge of the table 1. The threaded sleeves 8 are then actuated to bring the jaw 3 downwardly into clamping engagement with the upper face of the plywood sheet as clearly shown in Figure 4.

The valves 18, 19 and 20 are then opened and live steam obtained from the boiler 16 enters the steam pipes 12 and 13. The openings 14 cause jets of live steam to impinge against the channelled portion of the plywood sheet 21, thereby thoroughly saturating the channelled portion of the plywood sheet with steam, whereby the outwardly projecting portion of the plywood sheet may be easily bent down against the vertical face of the angular metal piece 2 to dispose the portions of the sheet on opposite sides of the channel 22 at approximately right angles to each other, as shown in Figure 5, and this with very slight pressure. When the lower steam pipe 13 is swung outwardly away from the table, the softened plywood sheet may be bent down against the front face of the table.

By operating the valves 19 and 20, jets of steam may be emitted from either or both of the steam pipes. While I prefer to use live steam, it is to be understood that the channelled plywood sheet may be heated and softened by any other desirable means for facilitating easy bending of the sheet.

Also, the plywood sheet may be bent to form a corner unit of any desired angular shape and I do not wish to limit myself to the forming of a 90° angle bend.

After the sheet of plywood material has been bent on the machine, it is removed from the table and placed in a jack (not shown) and the channel is then filled with a suitable filler such as a mixture of "Weldboard" glue and extender or any other binding cement, and when this is dry, the corner unit is ready for installation, in the manner fully disclosed in my aforementioned, pending application.

It will thus be seen from the foregoing description that I have devised an apparatus that will permit the easy and ready bending of a piece of plywood material for forming an angular corner unit and due to its simplicity the apparatus can be manufactured and sold at a low cost.

While I have shown the preferred embodiment of my invention, it is to be understood that various changes in the size, shape and arrangement of parts may be resorted to without departing from the spirit of the invention and the scope of the appended claims.

Having thus described my invention, what I claim is:

1. In an apparatus for forming angular corner units from pre-channelled plywood sheets, a table, a clamping jaw extending across the top of the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same.
- 5 2. In an apparatus for forming angular corner units from pre-channelled plywood sheets, a table, a clamping jaw extending across the top of the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 10 3. In an apparatus for forming angular corner units from pre-channelled plywood sheets, a table, means for securing the rear portion only of a pre-channelled plywood sheet thereon with the channelled portion of the sheet disposed outwardly of and adjacent the forward edge of the table, the free forward end portion of the plywood sheet extending outwardly from the front of the table, and perforated steam pipes arranged above and below the channelled portion of the plywood sheet for spraying live steam against the top and bottom faces of the channelled portion of the sheet simultaneously to soften the same and permit angular bending of the free forward end portion of the plywood sheet.
- 15 4. In an apparatus for forming angular corner units from pre-channelled plywood sheets, a table, a clamping jaw extending across the forward edge portion of the table, and adjustable gauge bar on the table for engagement with the rear edge of a plywood sheet placed on the table, said clamping jaw and gauge bar holding the rear portion of the plywood sheet on the table with the channelled portion of the sheet disposed outwardly of the forward edge of the table, and means for spraying live steam against the top and bottom faces of the channelled portion only of the sheet to soften the same and permit the angular bending of the free forward end portion of the plywood sheet.
- 20 5. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 25 6. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 30 7. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 35 8. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 40 9. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 45 10. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 50 11. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 55 12. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 60 13. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.
- 65 14. In an apparatus for forming angular corner units from pre-channelled plywood sheets, a table, a clamping jaw extending across the forward edge portion of the table to secure a pre-channelled plywood sheet thereon, with the channelled portion of the sheet disposed outwardly adjacent the forward edge of the table, a slidably adjustable gauge bar arranged on the table for engagement with the rear edge of the plywood sheet on the table, guide means for the slidably adjustable gauge bar, and upper and lower perforated steam delivery pipes arranged above and below the channelled portion of the sheet and extending for the full length of the channel for discharging steam against the channelled portion of the sheet to soften the same, the lower steam pipe being mounted for lateral swinging movement to permit the steam softened portion of the plywood sheet to be bent downwardly against the front edge of the table.

HAROLD McGOWAN,
